UNITED STATES PATENT OFFICE.

DANIEL J. GOLDEN, OF BROCKTON, MASSACHUSETTS, ASSIGNOR TO WALTER T. STALL, CHARLES H. DEAN, AND SAID DANIEL J. GOLDEN, A COPARTNERSHIP DOING BUSINESS AS GOLDEN SPORTING SHOE COMPANY, OF BROCKTON, MASSACHUSETTS.

SPORTING SHOES.

Application filed December 23, 1922. Serial No. 608,742.

To all whom it may concern:

Be it known that I, DANIEL J. GOLDEN, a citizen of the United States, residing at Brockton, in the county of Plymouth and State of Massachusetts, have invented new and useful Improvements in Sporting Shoes, of which the following is a specification.

This invention relates particularly to shoes such as those disclosed by my Patent No. 938,843, November 2, 1909, the outer surface of the tread portion of the outsole being provided with cleats, adapted to indent the ground and prevent slipping, and secured to the outsole and to the insole by fastening members passing through openings in a resilient pressure-supporting plate, usually of sheet steel, interposed between the two soles.

The object of the invention is to provide the plate, when used in a football shoe, with anchoring means adapted to securely engage fastening means engaged with a supplemental cleat, and cause the latter to prevent liability of displacement of the usual oblong cleats employed in football shoes, said oblong cleats presenting elongated sides, and being liable to be wrenched loose by pressure on said sides.

The said plate and the supplemental cleat anchoring means permit the employment of a supplemental cleat, adapted to resist all stresses and strains liable to displace the oblong cleats.

I attain the above-mentioned and other related objects, by the improvements herein-after described and claimed.

Of the accompanying drawings forming a part of this specification,—

Figure 1 is a side view of my improved pressure-supporting plate embodying the invention.

Figure 2 is a section on line 2—2 of Figure 1.

Figure 3 is a fragmentary sectional view, taken on the median line of the forepart of a welted shoe.

Figure 4 is a view similar to Figure 3, showing a McKay sewed shoe.

Figure 5 is a perspective view of the supplemental cleat.

Figure 6 is a perspective view of one of the oblong cleats.

The same reference characters indicate the same parts in all the figures.

In the drawings, 10 represents a resilient

pressure-supporting plate, formed to be interposed between the insole 12 and an outsole 13 of a sporting shoe, and provided with openings arranged to receive fastening members which secure cleats 15.

In a football shoe the cleats are oblong, and usually composed of sole leather lifts cemented together and secured by fastening members, such as nails 17, driven through holes formed for their reception in the cleats, and through openings in the plate 10, the fastening members as here shown, being clenched on the inner sole.

The openings in the plate 10 are in this case, oblong slots 18, arranged in the marginal portion of the plate, as shown by Figure 1.

The plate 10 is positioned on one of the soles before the soles are assembled and secured to each other and to the upper 19. In the welted shoe shown by Figure 3, the plate is first applied to the insole 12. In the McKay sewed shoe shown by Figure 4, the plate is first applied to the outsole 13.

To prevent liability of endwise and edge-wise slipping of the plate on the sole to which it is applied, I provide the plate with integral spurs 20, projecting from one side of the plate and adapted to enter the sole. In the welted shoe the spurs project inward and enter the insole, and in a McKay sewed shoe the spurs project outward and enter the outsole.

To enable the plate to be used with either of the described shoes, I form V-shaped slits 20^a, in the plate, these extending from side to side of the plate and forming the edges of V-shaped spurs 20. The operation of cutting the slits does not displace the metal forming the spurs, and leaves the sides of the spurs flush with the sides of the plate, so that the plate may be adapted for use in either make of shoe, by bending the spurs either outward or inward.

The oblong cleats 15 are arranged like the slots 18, so that their elongated sides face in different directions, these sides being often subjected to extreme pressure, tending to wrench the cleats from their operative positions. To overcome this objection I provide a supplemental cleat 22, and secure the same by a fastening member such as a screw 23 to an anchoring member such as an internally threaded annular boss 24, rigidly se-

cured to the central portion of the plate, the boss being internally threaded and adapted to engage the threaded portion of the screw 23, as shown by Figures 3 and 4. The central portion of the tread face of the outsole is provided with an orifice 25, receiving the boss 24. Said boss is preferably provided with an annular thin edged flange 26, attached by rivets 27 to the plate 10.

- 10 It will be seen that the boss 24 and the screw 23 engaged therewith, provide a strong connection between the supplemental cleat and the plate 10, confining the cleat against the tread face of the outsole, and adapted 15 to resist pressure exerted in directions which would be liable to displace the oblong cleats 15, the form of the supplemental cleat being such that it is adapted to resist pressure against any side of the cleat.
- 20 The supplemental cleat 22 is preferably formed as a truncated pyramid as shown by Figure 5, having side faces of uniform area and located at uniform distances from the screw 23, so that the supplemental cleat is 25 adapted, by its form, and by the screw 23 and the boss 24, whereby it is positively secured to the plate, to cause a uniform resistance to pressure, tending to tip the cleat in any direction.
- 30 It is desirable to provide the cleats 15 with two opposite side faces, each of major area exceeding that of either of the side faces of the cleat 22, and two side or end faces of major area, as may be seen by comparing 35 Figures 5 and 6. If the marginal cleats 15 were pyramidal, and each had been side faces of equal area, and if each cleat 15 were positively secured to the insole like the supplemental cleat, these cleats would be too 40 bulky, heavy, and clumsy, there being usually six cleats 15. The oblong form of the cleats 15 renders it necessary to secure each cleat by a row of nails, the thickness of these cleats being insufficient to permit the use of

relatively large attaching screws 23. It will 45 be seen, therefore, that the supplemental cleat 22 and the securing means therefor, characterized as above stated, enables said cleat, when embedded in the ground, to support the major portion of the strain exerted 50 on the series of cleats, and prevent liability of tipping displacement of the cleats 15 by strain exerted on their major side faces, and resisted only by the nails 17.

I claim:

In a shoe of the character stated, comprising an outsole, an insole and a resilient pressure-supporting plate interposed between said soles, and provided at its marginal portion with oblong openings, oblong 60 cleats projecting from the marginal portion of the tread face of the outsole, and nails extending through the oblong cleats and into the two soles and clinched in the insole; the described improvement comprising a supplemental cleat projecting from the central portion of the said tread face, and means positively securing the supplemental cleat to the supporting plate and clamping it against 65 said tread face, said means including an internally threaded boss having a flange riveted to the supporting plate, said boss projecting through an orifice in the outsole, and an attaching screw extending through the supplemental cleat and engaged with said 70 boss, the supplemental cleat being formed, and the said securing means adapted, to cause a uniform resistance to pressure tending 75 to tip the supplemental cleat in any direction, so that said cleat, when embedded in the ground, acts to prevent liability of displacement of the oblong cleats by pressure exerted on the major side faces of the latter.

In testimony whereof I have affixed my 80 85 signature.

DANIEL J. GOLDEN.
